CLAIM

The ornamental design for a suspender fastener, as shown and described.

DESCRIPTION

FIG. 1 is a front perspective view of the present design, shown in a position of use with a user;

FIG. 2 is a front view of the present design;

FIG. 3 is a right side view of the present design, a corresponding left side view being a mirror image thereof;

FIG. 4 is a rear view of the present design;

FIG. 5 is a bottom view of the present design; and,

FIG. 6 is a top view of the present design.

The broken lines shown in the drawings are included for the purpose of illustrating environmental structure and form no part of the claimed design.

1 Claim, 2 Drawing Sheets
